UNITED STATES PATENT OFFICE

154,524

DESIGN FOR A COMBINED DISPLAY AND
DEMONSTRATING UNIT

Albert E. Widdifield, Riverside, and Ivar Jepson,
Oak Park, Ill., assignors to Sunbeam Corpora-
tion, Chicago, Ill., a corporation of Illinois

Application May 22, 1948, Serial No. 146,534

Term of patent 14 years

(Cl. D80—9)

To all whom it may concern:

Be it known that we, Albert E. Widdifield and Ivar Jepson, both citizens of the United States, said Albert E. Widdifield being a resident of Riverside, county of Cook, and State of Illinois, and said Ivar Jepson being a resident of Oak Park, county of Cook, and State of Illinois, have invented a new, original, and ornamental design for a Combined Display and Demonstrating Unit, of which the following is a specification, reference being had to the accompanying drawings, forming part thereof.

In the drawings:

Figure 1 is a perspective view of a combined display and demonstrating unit, embodying our new design, showing the mirror supported in a low position;

Figure 2 is a perspective view of said unit, showing the mirror supported in an elevated position;

Figure 3 is a top plan view; Figure 4 is a side elevation; and Figure 5 is a front elevation there-
of.

We claim:

The ornamental design for a combined display and demonstrating unit, substantially as shown.

ALBERT E. WIDDIFIELD.
IVAR JEPSON.
